10 Claims. (Cl. 52—21)

This invention relates to the production of an ammonium nitrate base explosive charge which is capable of being poured or cast.

Explosive charges adapted to be poured (cast or molded) and having an ammonium nitrate base were widely used during the World War, whereby the exceedingly high melting point of the ammonium nitrate (167° C.) was lowered by the addition of related nitrates, for example, sodium nitrate and organic salts or substances such as sodium acetate, dicyandiamid and urea, until at about 105° C. a viscous mass was obtained which permitted sufficient homogenization with the aromatic substances, for example, trinitrotoluol added to increase the explosive force.

For producing this homogeneity it was necessary to maintain the melt in constant movement during the pouring of the charge. Such charges contained 20-25% trinitrotoluol.

It has now been found possible to produce ammonium nitrate base explosive charges of more complete homogeneity and still greater explosive force with equal safety in the gun barrel and on shooting at this explosive if the ammonium nitrate is melted together with the nitrates of simple or multiple amines of the aliphatic series. Thus, at temperatures at which there is no question of chemical decomposition, completely homogeneous and clear melts are produced, which cannot disintegrate (decompose or come out of admixture) and require no movement during the pouring. Such charges combine, with extremely great explosive force, which is superior to that of trinitrotoluol and picric acid, and with complete chemical stability a complete safety as well in the gun barrel as on shooting at the charge and they are thus easily the equals of the well known explosive charges of aromatic nitro bodies, for which reason they are generally suitable for artillery purposes.

Example I

Ammonium nitrate (melting point 167° C.)	55%
Ethylenediaminedinitrte (melting point 188° C.)	45%
Casting temperature	103° C.
Lead bloc expansion	390 ccm.

Example II

50 Ammonium nitrate (melting points 167° C.)	60%
Methylamine nitrate (melting point 109° C.)	40%
Casting temperature	58° C.
Lead bloc expansion	375 ccm.

Example III

Ammonium nitrate	55%
Ethylenediaminedinitrte	40%
Methylamine nitrate	5%
Casting temperature	93° C.
Lead bloc expansion	385 ccm.

Example IV

Ammonium nitrate	65%
Diethylenetriaminetrinitrate (melting point 151°)	35%
Casting temperature	116° C.
Lead bloc expansion	390 ccm.

70

Example V

Ammonium nitrate	55%
Ethylenediaminedinitrte	31.5%
Diethylenetriaminetrinitrate	13.5%
Casting temperature	105° C.
Lead bloc expansion	385 ccm.

75

Example VI

Ammonium nitrate	72%
Monoethanolamine nitrate (melting point 53°)	28%
Casting temperature	100° C.
Lead bloc expansion	320 ccm.

85

As compared therewith trinitrotoluol bulges out of a lead bloc only 290 ccm. and picric acid 310 ccm.

The formula of methylamine-nitrate is as follows:—

The formula of ethylene-diamine-dinitrate is as follows:—

In addition to the production of cast (molded or poured) charges for artillery purposes the above mentioned melt can also be used to advantage for industrial explosive purposes, when placed in the usual mining cartridges in pulverized form, as the explosives thus produced by reason of their great homogeneity, have greater efficiency and explosive force than the corresponding mechanical mixtures.

It is understood that various charges and modifications may be made in the above described process, and it is our intention to embody all such changes and modifications as may fall within the spirit of the following claims.

100

105

110

We claim:—

1. A process for the production of explosive mixtures of extremely great homogeneity, particularly for the production of poured explosive charges comprising melting together ammonium nitrate and nitrates of the amines of the aliphatic series. 80
5. A process for the production of explosive mixtures of extremely great homogeneity, particularly for the production of poured explosive charges comprising melting together ammonium nitrate and ethylenediaminedinitrate. 85
10. A process for the production of explosive mixtures of extremely great homogeneity, particularly for the production of poured explosive charges comprising melting together ammonium nitrate and methylamine nitrate. 90
15. A process for the production of explosive mixtures of extremely great homogeneity, particularly for the production of poured explosive charges comprising melting together ammonium nitrate and methylenediamine nitrate. 95
20. A new composition comprising the combination of ammonium nitrate and a nitrate of the amines of the aliphatic series. PHOKION NAOUM.
5. A new composition comprising ammonium
